UNITED STATES PATENT OFFICE

OSCAR H. PIEPER, OF ROCHESTER, NEW YORK

INSTRUMENT HOLDER

Application filed April 2, 1926, Serial No. 99,296. Renewed December 16, 1929.

This invention relates to instrument holders which are particularly useful in connection with dental units for holding the various low voltage heating instruments, mouth 5 lamps, and other tools or devices. Heretofore, the various heating instruments, lamps and other dental tools have been attached to the instrument handles by ordinary screw threads, and in some cases by a 10 bayonet joint. The objections to these arrangements are that too much time is consumed in turning the bases of the tools or instruments into or out of the handle or grip of the holder. Another disadvantage and 15 objection is that the instrument or tool will always have the same position relative to the electric controlling switch button, and this is not always most desirable or convenient in the manipulation of the holder.

20 The object of the invention is therefore to overcome all these objections by providing improved holding arrangement or joint between the instrument or tool and the grip or handle part which will permit the instrument or tool to be quickly inserted or removed and which will also permit the instrument or tool to be easily turned to the desired position relative to the switch button while the instrument is being used. This is accomplished by means of a split collet in the mouth of the handle, and a tapered shank or plug on the base of the instrument or tool. The structure will be more fully understood 25 by reference to the drawings, on which,

25 Figure 1 is a side elevational view of a dental holder and tool;

Fig. 2 is an enlarged sectional view on plane 2—2 of Figure 1;

Fig. 3 is an enlarged side elevational view 30 of the split collet;

Fig. 4 is an inner end view of the collet;

Fig. 5 is a side elevational view of the instrument base; and

Fig. 6 is a sectional view on plane 6—6, 35 Figure 2.

In the structure shown the tubular handle or grip part 10 has the sleeve 11 which supports the contact button 12 which is readily slidible in the sleeve and through the slot 50 13 in the handle, and the longitudinal slid-

ing motion of the tubular handle is limited by the extent of the slot 13. Within the tubular handle is circuit controlling mechanism comprising the supporting body 14 of insulating material and the terminal springs 55 15 and 16 mounted thereon, the support being held within the tube by a screw 17 and the terminal springs connecting with the circuit cord 18 which extends through the plug 19 at the end of the tubular handle.

In the front end of the handle tube is inserted the collet or thimble structure designated as a whole C. The body 20 of this collet is threaded to detachably engage in the threaded end of the handle tube, the engagement of the collet in the tube being limited by its head 21. The inner end of the collet is of reduced external diameter to be displaced a distance from the tube wall and to form a thin skirt which is divided into flexible segments 22 by the slits 23.

The base 24 of the instrument or tool has the shank or plug extension 25 for fitting into the collet C. The inner end of the shank which engages in the skirt section of the collet is preferably cylindrical and in order that the spring sections of the skirt may clamp the shank end the end may be of slightly larger diameter than the skirt or the skirt can be radially contracted after being slotted. The outer end of the shank is preferably tapered slightly and the outer end of the collet is tapered to correspond. The object of this is to save making an extremely accurate fit between the two parts which would be necessary if both parts were straight. Ordinarily, the slit skirt end of the collet will exert efficient clamping action on the shank to lock the instrument or tool against displacement during use. The tapered surfaces of the base and collet will serve to lock the tube more rigidly and securely to the collet when desired. The instrument base may be readily turned to seat in the collet or to be removed therefrom, or to be adjusted relative to the collet, the base being preferably knurled as indicated at 26 to afford a better hold.

The instrument end or point 27 is inserted in the front end of the base 24 and is hollow for receiving the electric heat element 28. 100

This element extends through an insulating bushing 29 in the base and one terminal of the element connects with the terminal tip 30 extending from the bushing 29. The other end 5 of the heating element connects to the terminal sleeve 31 surrounding the terminal tip 30 and secured in the end of the base 24. When the tool structure is inserted into the handle or grip part, the terminal sleeve 31 will engage with the terminal spring 16 of the switch mechanisms within the handle, and upon depression of the button 12 the terminal spring 15 will be brought into electrical contact with the terminal tip 30 so that the electric supply 10 circuit will be closed through the electric heat element and this element will then supply the necessary heat for the tool point. When the instrument structure is inserted into the handle or grip part, the split collet will hold the 15 base of the instrument tight enough so that the instrument will not come out nor turn as a result of any pressure applied to it in the usual dental practice, and by means of the knurling on the instrument base the instrument 20 can be readily turned into any position desired relative to the switch button 12 on the handle. No time is wasted in applying a tool or instrument as a mere push or pull will serve to apply it to the handle or to remove it 25 therefrom.

I claim as follows:—

1. An instrument structure of the class described comprising a handle part and an instrument part, said instrument part comprising a base having an operating tool extending from the outer end thereof and a shank extending from the inner end thereof, and a collet threaded into the end of said handle part to form a socket for receiving 35 said shank, the inner end of said collet being entirely clear of the handle part wall and being split to form elastic segments for clamping said shank to thereby hold said instrument part in operative position relative to the handle part.

2. In an instrument structure of the class described, the combination of a tubular body part and an instrument part, said instrument part comprising a base having an operating tool extending from the outer end thereof and having a shank at its inner end, a collet threaded into the end of said tubular handle part to form a receiving socket for said shank, the inner end of said collet being entirely spaced away from the handle part wall and being split to be radially elastic, said elastic section of the collet receiving the outer end of said shank to hold the instrument part in operative position relative to said handle 50 part, the outer end of said collet being tapered and the inner end of said shank being correspondingly tapered, said tapered sections interfitting.

3. In an instrument structure of the class 55 described, the combination of a tubular han-

dle part and an instrument part comprising a base having an operating tool at its outer end and a shank at its inner end, an electric heating element extending through said tool and base and terminals therefor at the inner end of said shank, a collet inserted in the end of said handle part and being spaced at its inner end entirely away from the handle part wall and being slotted longitudinally to provide clamping tongues, said shank fitting into said collet to be clamped by said tongues, circuit terminals within said handle part, and a push button controlling the operative connection of said circuit terminals with said heating element terminals, the clamping engagement of said tongues with said shank being sufficient to lock said instrument part in operative position relative to said body part but permitting positive rotation of said instrument part for adjustment thereof relative to said push button.

4. In an instrument of the class described, the combination of a tubular handle part, a socket member forming part of and secured in the open end of said handle part and having a tapered bore, a split skirt extending from said socket member forming a continuation of said tapered bore and being clear of the handle part wall to be radially yieldable, and an instrument part comprising a base having a shank extending therefrom, said shank at its end being cylindrical to engage in said split skirt and above said end being tapered to fit the tapered bore of said socket.

In witness whereof, I hereunto subscribe my name this 29th day of March, 1926.

OSCAR H. PIEPER.
